UNITED STATES PATENT OFFICE.

WM. G. PIKE AND ISAAC R. SCOTT, OF WALTHAM, MASSACHUSETTS.

SAFETY APPARATUS FOR REGULATING STEAM-BOILER FURNACES.

Specification of Letters Patent No. 17,636, dated June 23, 1857.

To all whom it may concern:

Be it known that we, WILLIAM G. PIKE and ISAAC R. SCOTT, of Waltham, in the county of Middlesex and State of Massachusetts, have invented an Improved Safety Regulating Apparatus for Furnaces for Heating Buildings by Steam, of which the following is a full, clear, and exact description, reference being had to the annexed 10 drawings, making part of this specification, in which—

Figure 1 is a perspective view of the furnace and boiler of a steam-heating apparatus having our improvements attached; Fig. 2, 15 detail to be referred to hereafter.

Efforts have been made to regulate the intensity of the fire and consequently the amount of steam generated in steam heating boilers by closing the dampers of both the 20 draft and smoke flues, by connecting them to a float in a detached chamber of water in communication with the boiler; but with such an arrangement it has not been found practicable to establish a pressure in the 25 boiler of even a few pounds, as the height of the column of water necessary for the purpose would be inconveniently great, and in case of an excess of pressure the generation of steam will throw the water out of the 30 boiler through the float chamber.

To obviate this and yet to render the boiler perfectly safe under a pressure sufficient for any heating purposes is the object of our present invention, which will now be 35 more fully explained.

In the said drawings A is a casing containing a boiler of the ordinary construction, B is an opening to the fire box. From the top of the boiler rises a pipe C that carries the 40 steam to the radiators which heat the building, from which the water of condensation is returned to the boiler by the pipe D. The pipe E leads to the reservoir which supplies the boiler. A cock F serves to empty the 45 boiler when necessary. a are gage cocks for testing the height of water in the boiler. As these details form no part of our present invention, they need not be further described.

G are dampers in the pipes H and I, the 50 one being the smoke pipe, the other that which admits air for the supply of combustion. These dampers are connected together by the rod e and are weighted to open themselves.

Connected to the pipe C immediately 55 above the boiler is a short pipe K, on the top

of which is a safety valve b, and from the pipe K near its top lead the pipes L and M, the former leading from the boiler directly to the regulating apparatus, and the latter 60 permitting a flow of steam from the boiler onto the fire through the nozzle f whenever the safety valve b is raised, another pipe N connects the pipe M and consequently the nozzle f with the upper part of the regulator, 65 which will now be described.

A bent pipe O is connected at one end to the pipe L and hangs outside of the boiler case A. The other end of the pipe O is open at e, where it is carried up as high 70 as is necessary to contain a sufficient column of mercury to resist the maximum pressure of steam at which the boiler is intended to be used (the mercury is seen dotted in blue in Fig. 1). The open end of the pipe 75 O is embraced by a jacket P of a considerably larger diameter than the pipe O. It also extends up above the open end e and is closed at top and bottom, the bottom at g embracing the pipe O. The pipe N is connected to the jacket P near its top. The top is closed by a screw plug h, from which rises a standard Q, the end of which is bent over at i. Through this bent part i and through the plug h passes a rod k, to the lower end of 80 which is attached a float m, which rests on the column of mercury in the pipe O. The upper end of the rod k passes through a block n, which is secured to the rod by a screw o passing through the block. A rod l 90 passes horizontally through the block n and has attached to each end of it a chain p. These chains are connected to the damper G in the pipe H. The rod k may be adjusted in the block n and be secured by the screw o. 95 This adjustment fixes the height to which the mercury shall be raised by the pressure of the steam before the dampers G are closed by the raising of the rod k. A scale may be placed on the standard Q and an adjustable 100 index may be attached to the rod k which will always show the pressure in the boiler. The pipe N connects the upper part of the jacket P with the pipe M.

The operation of our regulating safety 105 apparatus is as follows: The parts being adjusted as before explained so that the dampers will be closed when the pressure in the boiler exceeds the desired amount, the safety valve b is set to blow off at a definite 110 pressure (say of 4 lbs.). When this valve is raised the steam passes through the pipe M

and nozzle *f* into the fire box and dampens the fire. The end *e* of the pipe *O* is carried to such a height that a pressure rather exceeding that to which the valve *b* is adjusted (or say of 6 lbs.) will raise the column of mercury in it to the top of the pipe, so that if by any accident (such as adhesion to its seat) the valve *b* fails to operate and the pressure increases beyond the 6 lbs. the mercury will be blown out of the pipe *O* and fall over into the bottom of the jacket *P*, the steam escaping through the open end of the pipe *O* and through the pipes *N* and *M* and nozzle *f* into the fire box, extinguishing the fire. This entirely precludes the possibility of an explosion, as the pressure in the boiler can in no instance exceed the limit to which it is fixed by the height of the column of mercury employed. The pressure may however be fixed at a given amount within this limit (say at 3 lbs.) and be maintained with great uniformity by means of the dampers *G*, the rod *k* being adjusted in the block *n*. So soon as the pressure increases and the column of mercury rises in the pipe *O* the rod *k* will through the connection of the chains *p* close the dampers *G* and check the intensity of the fire, and as the pressure decreases the rod *k* will fall and the dampers will be allowed to open. When the mercury has been blown over into the jacket *P* by an excessive pressure, it may be drawn off by the cock *S*, to be again returned to the pipe *O*. In lieu of this arrangement for recovering the mercury when blown out of the pipe *O* we propose to sometimes use the device represented in Fig. 2, where the jacket *P* is enlarged, forming a flat box *R* the bottom of

which embraces closely the end of the pipe *O*, the end rising about $\frac{1}{8}$ of an inch or thereabout above the bottom of the box *R*. A notch is cut down in one side of the pipe as at *s* as low as the bottom of the box. Thus after the mercury has been blown out of the pipe *O* over into the box *R* and the steam has escaped the mercury may run back again through the notch *s* into the pipe *O* without the trouble of having to replace it. This regulating apparatus thus becomes a positive and unerring safety valve, as the pressure can at no time exceed that produced by the column of mercury employed.

We do not claim regulating the intensity of furnace fires by closing the dampers in the draft and smoke pipes by means of a float within a water chamber in communication with the boiler, as we employ no such contrivance; but

What we do claim as our invention and desire to secure by Letters Patent is—

The within described arrangement of the bent mercury tube *D* with its float and the parts immediately connected therewith, and the steam pipe *f*, whereby the pressure within the boiler is indicated to the eye, the dampers are regulated to suit the pressure required, and when the pressure within the boiler becomes excessive the fire is extinguished by the escaping steam, thereby forming a safety regulating apparatus, not requiring the supervision of the attendant.

WM. G. PIKE.
ISAAC R. SCOTT.
